UNITED STATES PATENT OFFICE

167,734

TELEPHONE UTILITY CABINET

Benjamin Applebaum, Buffalo, N. Y.

Application April 10, 1952, Serial No. 19,280

Term of patent 14 years

(Cl. D33—3)

To all whom it may concern:

Be it known that I, Benjamin Applebaum, a citizen of the United States, residing at Buffalo, in the county of Erie and State of New York, have invented a new, original, and ornamental Design for a Telephone Utility Cabinet, of which the following is a specification, reference being had to the accompanying drawing, forming a part thereof.

Figure 1 is a perspective view of the cabinet embodying my design.

Figure 2 is a top plan view of the same.

Figure 3 is a rear view thereof.

I claim:

The ornamental design for a telephone utility cabinet, substantially as shown.

BENJAMIN APPLEBAUM.
